INVENTOR.

Geo. B. Owen,

Dec. 1674

George B. Owen, of New York, N.Y.
Letters Patent No. 1674 Dated Nov. 11th 1862.

The schedule referred to in these Letters Patent and making part of the same,

Des. 1674

To all whom it may concern:

Be it known that I, George B. Cown of the City, County and State of New York, have invented or produced a new and original Design for a Clock case, and I do hereby declare that the following is a full, clear and exact description of the same, reference being had to the accompanying drawings, making a part of this specification, in which

Figure 1 is a front elevation of a clock Case constructed according to my design.—

Figure 2 a Horizontal section of the same, taken in the line x. xc Figure 1.—

Similar letters of reference indicate corresponding parts in the two Figures.—

This clock case is formed with two ends A. A. of curved form, each being a quarter circle in their horizontal section, and a plane B which connects the two ends A. A and forms the central part of the front of the case.—

The top of the ends A. A and centre B, are provided with a moulding C which is composed of an ovolu a with a fillet b beneath it and a cyma-reverse c above it, the cyma-reverse having a fillet d above it, which is surmounted by an ovolu e, with two fillets f. g, above it, the latter not projecting as far outward as the former.—

The portion of the moulding C which is over central part B of the case projects a trifle farther outward than that which is over the curved ends A. A forming a break h at each side of the central portion of the moulding, and

said portion of the moulding C not having the ovoli
a fillet ℓ and cyma-reversa $\mathfrak{c}$, at its lower
part, their place being provided with other
parts herein after described.—

The clock case is also provided
with a moulding D at its base which is at the low-
er parts of the curved ends A, A. only.— This
moulding D is composed of an ovoli i at its bottom,
and an ovoli j at its upper part or top, the ovoli
 j having a cyma-reversa $\mathfrak{k}$ above it, and the lat-
ter a fillet $\mathfrak{j}$ above it.

At the lower part of the centre B of
the clock case between the two parts of the moulding
D there is a square panel $\mathfrak{l}$ in which there secured
longitudinally and centrally an oblong projection
 m of triangular form in its transverse section,
and having bevelled ends.— The edges or sides of the
panel $\mathfrak{l}$ are formed of a moulding composed of
an ovoli n , ogee $\mathfrak{o}$, ovoli p and fillett q , see
Figure 1.—

Directly above the panel $\mathfrak{l}$ there is an
oblong rectangular projection $\mathfrak{r}$, on the upper
surface of which there is an ovoli x having rounded
ends, and an ovoli bead y on its front or face side.—

At each side of the centre B of the clock case there is a pilaster s ,
having a vertical ovoli t attached to it, and at
the upper part of the centre just below the ovoli e
there is a fascia u on which there are two square
projections u, v , one near each end, and a
square projection w at its centre having a hor-
izontal projection a' at each side of it of semi-
conical form.

The main parts of the curved ends A, A.

Dec. 1674

of the clock case are provided with panels b in the centre of which there are secured vertical ovoli beads c,

Having thus described my invention, what I claim as new, and desire to secure by Letters Patent, is, -

The general configuration of the parts, as herein shown and described, to form a new and original design for a clock case, -
